LLP(57) **CLAIM**

The ornamental design for a saddle pad, as shown and described.

DESCRIPTION

FIG. 1 is a perspective elevational view of my new saddle pad;

FIG. 2 is a top plan view of my new saddle pad of FIG. 1; and,

FIG. 3 is an enlarged view of a section of my new saddle pad of FIG. 1.

The evenly broken lines in the drawings are for the purpose of illustrating portions of the article that form no part of the claim.

The dash-dot-dash broken lines in the drawings are boundary lines for the purpose of illustrating portions of the claim boundary wherein the portions within the dash-dot-dash lines are claimed and the portions outside of the dash-dot-dash lines form no part of the claim.

1 Claim, 3 Drawing SheetsFIG. 1

FIG. 2

FIG. 3
